UNITED STATES PATENT OFFICE.

EDWARD J. BRANDT, OF WATERTOWN, WISCONSIN, ASSIGNOR TO BRANDT CASHIER COMPANY, OF CHICAGO, ILLINOIS, A CORPORATION OF ILLINOIS.

DESIGN FOR A CASING FOR COIN-DELIVERY MACHINES.

43,134.

Specification for Design.

Patented Oct. 15, 1912.

Application filed August 13, 1912. Serial No. 714,904. Term of patent 14 years.

To all whom it may concern:

Be it known that I, EDWARD J. BRANDT, a citizen of the United States, residing at Watertown, in the county of Jefferson and State of Wisconsin, have invented a new, original, and ornamental Design for a Casing for Coin-Delivery Machines, of which the following is a specification, reference being had to the accompanying drawing, forming part thereof.

Figure 1 is a perspective view, and Fig. 2 is a side elevation.

I claim:

The ornamental design for a casing for coin delivery machine, as shown.

EDWARD J. BRANDT.
